JOHN CROSS FIELD, OF LUTCHER, LOUISIANA.

SAFETY SPLIT SET COLLAR.

1,391,727.

Specification of Letters Patent. Patented Sept. 27, 1921.

Application filed June 26, 1920. Serial No. 392,030.

To all whom it may concern:

Be it known that I, JOHN CROSS FIELD, a citizen of the United States, and a resident of Lutcher, in the county of St. James and State of Louisiana, have invented certain new and useful Improvements in Safety Split Set Collars, of which the following is a specification.

This invention relates to improvements in set collars, and more particularly to a split set collar designed to afford safety to persons working about machinery, so as to prevent catching one's clothing thereon and obviating the danger of wrapping or winding clothing thereon and causing injury, due to the fact that the device has no open spaces on its face or protruding screws or bolts as in the ordinary set collars.

A further object of the invention is to provide a safety split set collar which may be quickly installed without removal of the shaft, being adapted to be installed or removed in view of its simplicity, in a minimum of time, as well as requiring a space 25 for installation of its own width only and affording an absolutely smooth exposed surface.

A still further object of the invention is to provide a novel form of joint between the 30 sections of the split collar which obviates the necessity for employing bolts and adapts the safety covering to be applied without projecting parts while at the same time facilitating the application of the set collar to a shaft to which the same is secured by the 35 ordinary set screw, while the covering or safety shield can be applied to solid or single-piece collars with absolute safety.

Among others, it is also an object to provide 40 a device which can be very economically produced and which is both strong and durable, and not likely to get out of order.

Other and further objects of my invention will become readily apparent to those skilled 45 in the art from a consideration of the following description, when taken in conjunction with the accompanying drawings, wherein:

Figure 1 is a perspective view of my improved safety split set collar,

Fig. 2 is a cross section thereof, and

Fig. 3 is a fragmentary transverse sectional view showing the covering or shield.

As illustrated, the improved set collar comprises sections 10 and 11 of semi-circular form, adapted to fit a shaft or the like, for the purpose of preventing side play or lat-

eral motion adjacent to a bearing box, thus preventing end thrust of the shaft or the like. The section 10 is provided at one end with a curved projection or hook 12 which 60 extends from a point adjacent to the inner face thereof outwardly substantially at right angles and is tapered toward its free end which is positioned slightly within the peripheral surface of the collar. The adjacent 65 end of the opposite section 11 is provided with a similarly shaped recess 13 open at its inner edge, as indicated at 14, and adapted to pivotally and movably receive the hook 12 therein as clearly shown in Fig. 2 of the 70 drawings, in order to prevent separation of the sections in a direction of the plane of the coacting ends or faces 15.

The opposite end of the section 10 is provided with a threaded socket 16 and at a 75 point spaced from the opposite end of the section 11 and at the periphery thereof, there is provided a right angular notch or recess 17 having a threaded aperture 18 for receiving a cap screw 19, thus permitting the sections to be fastened together with a single 80 screw, although it is to be understood that the collar may be made in one piece or section if desired and that the connecting means 19 may be modified as desired. 85

The safety covering or shield for the cap 90 comprises semi-circular flange sections 20, preferably of sheet metal, having the flanges 21 thereof directed outwardly at obtuse angles. At a point intermediately of the ends 90 of the section 10, there is provided an apertured plate 22, the plate being secured in position by means of a screw 23 engaging a corresponding socket extending radially of the section 10 and the apertures thereof being in the form of slots 24 pivotally receiving the reduced sleeve forming tongues 25 at the ends of the section 20 so that the latter may be opened into positions in alignment with each other and away from the 100 sections 10 and 11 of the collar.

At a point diametrically opposite the section 11 of the collar is provided a recess 26 designed to receive the inwardly offset ends 27 of the covering or shield sections 20 105 therein, the side flanges being omitted at the hinge connection and at the offset portions 27, which latter are apertured to receive a securing screw 28, having disposed at the outside, a plate 29, in order that the 110 surface will be relatively smooth and thereby avoid all depressions or projections com-

mon in devices of this character. There is also provided a threaded radial opening 30 by means of which a set screw may be applied for securing the collar to a shaft 5 or the like against turning or longitudinal movement, thus preventing side play or lateral motion of the shaft or part held by the collar. It is also to be understood that the set screw is secured in position in the 10 opening 30 and jammed or forced against the shaft or the like, before the shield or shield sections are fastened in position to cover the same and the fastenings. It should also be noted that the side edges of the sections 15 10 and 11 are recessed or rabbeted as indicated at 31, in order to receive the oppositely inclined flanges 21 of the shield or covering sections, which are thus held from lateral displacement when secured in position 20 as described.

It will also be apparent that when the device is in use, the sections may be independently applied to a shaft and connected as described, after which the shield or covering sections 20 are swung into position and secured by the set screw 28. The hook 12 is first engaged with the recess 13, after which the abutting ends are connected by the cap screw 19, the covering or shield sections 25 being subsequently swung from open to closed positions in order to envelop the collar, whereby the sections of the latter are held in assembled relation. It will also be understood that the covering or shield sections 30 may be applied to a single piece collar and it will be seen that the construction described permits quick installation or removal of the collar, as well as furnishing perfectly smooth surfaces on the face and 35 on both sides without protruding screws or bolts, such as in ordinary set collars, thus avoiding the danger of wrapping or winding one's clothing thereon and reducing the liability of injury to a minimum. The hook 40 45 joint connecting the sections of the collar also obviates the necessity of employing flanges or the like on the collar sections in split types of collars or connecting the same by means of bolts requiring considerable 50 time for application and removal and which are otherwise objectionable.

In view of the foregoing, it is thought that the operation of the device will be readily understood, and in view of the simplicity and practical value that it will commend itself to those skilled in the art.

Having thus described my invention, I claim:

1. A set collar including a collar proper 60 having a pair of recesses substantially diametrically opposed to each other at the periphery thereof, a slotted plate secured in one recess, a substantially semi-circular flanged shield section having an extension 65 hinged in the slot of said plate, and having

its opposite end offset inwardly to engage the other recess, a plate over said offset end, and securing means passed through said plate and offset end and engaged with the collar.

70

2. The combination with a collar body having rabbeted edges at the sides of the periphery thereof providing a projecting intermediate portion; of a covering section having side flanges engaging said intermediate portion with the flanges thereof disposed against the side edges of said intermediate portion, one end of the covering section being hinged and detachably connected to said intermediate portion, and means detachably 80 securing the opposite end of said covering section to the intermediate portion.

75

3. A set collar comprising a collar body proper, and a safety shield therefor comprising hinged sections adapted for movement in opposite directions in a plane normal to the surface of the collar and to envelop the same, and means for connecting the free ends of said shield sections to each other and to the collar body.

85

4. The combination with a collar having projecting intermediate portions producing recessed side edges, said collar having diametrically opposed recesses at the periphery of said intermediate portions; of a safety shield therefor, said shield comprising a plate secured in one of said recesses, semi-circular flanged shield sections hinged to the ends of said plate and adapted to swing in alinement when open and to fit around 100 the collar when closed against the same, the free ends of said sections having inwardly offset portions, a plate over said offset portions, and means securing the offset portions and plate together and to the collar.

95

5. A safety split set collar comprising a pair of hinged collar sections detachably connected and adapted to be swung to separated positions, and a safety shield therefor comprising hinged sections and means for 110 securing the free ends of said sections to the collar sections.

105

6. A safety split set collar comprising semi-circular collar sections having their ends disposed in abutting relation, one end 115 of one section being provided with an outwardly extending hook and the other end with a recess detachably and pivotally engaged by said hook, a cap screw connecting the other ends of said collar sections and embedded in the peripheral face of one, and a safety covering for the collar comprising hinged sections and means for detachably securing the same in position.

120

7. A safety split set collar comprising 125 semi-circular collar sections having their ends disposed in abutting relation, one end of one section being provided with an outwardly extending hook and the other end with a recess detachably and pivotally en- 130

gaged by said hook, a cap screw connecting the other ends of said collar sections and embedded in the peripheral face of one, said collar sections having rabbeted side edges 5 producing a projecting intermediate portion circumscribing the collar, an apertured plate secured to the projecting portion of one section of the collar intermediately of the ends thereof, sheet metal covering sections having reduced extension sleeves pivoted to said plate at its opposite ends and having side flanges engaging the sides 10 of the projecting portions of the collar sec-

tions, the free ends of the covering sections being offset inwardly, the intermediate 15 portion of the periphery of the other collar section having a recess engaged by said offset portions, a plate disposed over said offset portions flush with the peripheral surfaces of the cover sections, and a screw 20 passed through said plate and offset portions and engaged with the collar section adjacent thereto, one of said sections having a threaded aperture for receiving a set screw beneath the cover section.

JOHN CROSS FIELD.
